UNITED STATES PATENT OFFICE.

ARTHUR R. MACKENZIE AND FREDERICK W. WATSON, OF BROOKLYN, NEW YORK.

BELL.

Application filed May 19, 1923. Serial No. 640,005.

To all whom it may concern:

Be it known that we, ARTHUR R. MACKENZIE and FREDERICK W. WATSON, both citizens of the United States, and residents of 5 Brooklyn, in the county of Kings and State of New York, have invented certain new and useful Improvements in Bells, of which the the following is a specification.

This invention relates to bells and more 10 particularly to small bells or gongs of portable, hand operated type used in producing a musical sound when agitated to the extent of causing the clapper or tongue to strike the body or casing shell.

15 The principal object of the invention is to produce a bell having a flexible handle which may be bent, or folded in any direction without detriment and which permits stowing the bell in an exceedingly compact man- 20 ner.

A further purpose is to produce a bell particularly designed as an attractive novelty or fun producer at public gatherings and the like, the flexible handle readily lending 25 itself for attachment purposes impossible to bells having rigid unyielding handles.

Another aim is in the provision of a bell which can be made in the representation of certain articles of dress and wearing apparel such as head coverings, as for instance 30 a fez or turkish cap, of which the present embodiment is a reproduction in miniature including the tassel.

These and other analogous objects, aims 35 and purposes are accomplished by the novel construction, combination and arrangement of parts hereafter described and shown in the accompanying drawing, forming part hereof, and in which:—

40 Figure 1 is a perspective view showing an embodiment of the invention and indicating the manner in which it is used.

Figure 2 is a similar view drawn to a diminished scale and showing another application. 45

Figure 3 is a side elevational view, partially broken away to show the construction.

As shown in the drawing, the body or casing shell 5 of the bell is preferably a hol- 50 low cone, open at its larger, lower end and closed at its top 6 which has a central perforation 7.

A highly flexible cord 8 is doubled upon itself and has attached at its ends, by a suitable knot 9 or otherwise, a tassel 10 which 55 acts as the handle of the bell.

The bight 11 of the cord is passed through a split tubular sleeve 12 and thence through the perforation 7 into the interior of the bell. 60

Here the bight is engaged by a split ring 13 which also contains the eye 14 of the link 15 carrying the tongue or striker 16, which is thus free to swing in any direction and make contact with the interior of the bell to 65 produce sound.

When the assemblage has been effected the sleeve 12 is tightly closed upon the cord preventing it from being drawn into the bell body, whereupon it is ready for use. 70

Besides the ordinary service as a signal device as shown in Figure 1, the bell may be attached to the garments of individuals by passing a safety pin 17 or the like through the cord as illustrated in Figure 2, so that 75 the bell will be sounded by the movements of the user.

It will be understood that the body of the bell may be made of any suitable material, finished by polishing, plating or enamelling 80 in any desired colors and bear such ornamentation as may be preferred, as suggested in Figure 1; also that the cord and tassel may be of silk or other material and of such color as fancy dictates. 85

It will be apparent that the handle which includes the cord and tassel, may be compactly folded closely about the top of the bell so that substantially no extra space is required for it and it will be equally clear 90 that this flexible handle will perform all the functions of rigid handles besides being more pleasing to the touch.

Although we have described our improvement with considerable detail and with respect to certain particular forms of our invention, we do not desire to be limited to such details since many changes and modifications may well be made without departing from the spirit and scope of our invention in its broadest aspect. 95

Having thus described our invention, what we claim as new and desire to secure by Letters Patent, is:— 100

A bell of the class described and a flexible handle therefor, said handle being composed of a doubled cord having a tassel united therewith, the bight of said cord 5 passing through the top of the bell, an open ring connected in the bight of said cord the tongue of said bell being engaged in the ring, and a split sleeve clamped on said cord to retain it in place, said sleeve resting on

top of the bell, and holding said ring ¹⁰ tightly against the top of the bell.

This specification signed and witnessed this 17th day of May, 1923.

ARTHUR R. MACKENZIE.
FREDERICK W. WATSON.
